UNITED STATES PATENT OFFICE.

GEORGE E. RANDLE, OF CLEVELAND, OHIO, ASSIGNOR TO THE FOOTE-BURT COMPANY, A CORPORATION OF OHIO.

REVERSING GEARING FOR CLOTHES WRINGERS.

Application filed May 27, 1924. Serial No. 716,253.

To all whom it may concern:

Be it known that I, GEORGE E. RANDLE, a citizen of the United States, residing at Cleveland, county of Cuyahoga, State of Ohio, have invented certain new and useful Improvements in Reversing Gearing for Clothes Wringer, of which the following is a specification.

The present invention relates to clothes wringers such as are used in connection with power driven washing machines, and especially to the reversing mechanism for such wringers which is provided in order to enable the wringer rolls to be operated in either direction.

The object of my invention is to provide an improved reversing gearing for a wringer which gearing is simple in structure, comprises few parts so it may be manufactured at a low cost, is easy to assemble, and is small and compact.

For a consideration of what I believe to be novel and my invention attention is directed to the accompanying description and the claims appended thereto.

In the drawing, Fig. 1 is a side elevation partly in section of a wringer provided with a reversing gearing embodying my invention, and Fig. 2 is a perspective on a larger scale of the gearing.

Referring to the drawing, 1 indicates generally a wringer which may be of any suitable type. The rolls of the wringer are shown at 2, the drainboard at 3, and the two gear wheels which connect the wringer rolls together at 4. The bearings for the wringer roll shafts 5 are indicated at 6. The shaft 6 of the lower roll projects beyond its gear wheel 4 and is provided with a rectangular end 7 which enters a rectangular opening 8 in a coupling member or sleeve 9.

At 10 is indicated a gear casing or gear box. It comprises a top 11, a bottom wall 12, and side walls 13 formed integral with each other. It is open at its inner end as indicated at 14 and in its four corners are pads 15 which receive screws 16 by means of which the casing is attached to end flanges 17 on the wringer frame. At the center of the casing is a partition wall 18 provided with a bearing 19 in which is mounted a stub shaft 20 which carries a crown gear wheel 21. At its inner end shaft 20 is provided with a rectangular tongue 22 which enters a rectangular opening 23 in coupling member

9. Coupling member 9 thus serves to connect the crown gear wheel 21 to the lower wringer roll shaft 5. The front end of casing 11 is closed by a cover plate 24 held in place by screws 25.

In the top wall 11 of the casing is an opening 26 in which is mounted a bearing bushing 27 held in position by a projection on the end of upper screw 25 which enters an opening 28 in the bearing bushing. On the lower wall 12 of the casing is a sleeve 29 provided with a bearing portion 30 in line with bearing bushing 27 and a socket 31 which fits over a stationary tube 32 and on which the wringer may swing. At 32^a is a spring pressed pin carried by sleeve 29 and adapted to engage openings 32^b in the top of tube 32 for holding the wringer in the desired adjusted positions. Tube 32 may be one of the frame tubes of a washing machine or other suitable supporting element. In tube 32 is a wringer driving shaft 33 driven from the motor of the washing machine (not shown). For example, the arrangement shown in my application Sr. No. 591,400, filed September 29, 1922 may be used. The upper end of driving shaft 33 is provided with a rectangular end 34 which fits into a rectangular coupling sleeve 35.

Mounted in bearings 27 and 30 is a vertical shaft 36 on which are two fixed pinions 37 and 38 adapted to mesh with crown gear wheel 21. As will be noted pinions 37 and 38 are mounted within the confines of crown gear 21. When shaft 36 is moved upward from neutral position pinion 37 is brought into mesh with crown gear wheel 21 and when shaft 36 is moved downward from neutral position pinion 38 is brought into mesh with crown gear wheel 21. The lower end of shaft 36 is provided with a squared end 39 which fits into the upper end of coupling sleeve 35 to connect shaft 36 to driving shaft 33. In the side of shaft 36 at its upper end is a groove 40 which forms a passage for the escape of air from the end of the bearing bushing.

Engaging shaft 36 and pinions 37 and 38 is a shifter block 41 comprising a front wall 42 from which project upper and lower forks 43 and 44 which surround shaft 36 at opposite ends of the pinions and a central fork 45 which fits between the pinions. Wall 42 has forwardly projecting flanges 46 which engage and slide upon the inner face 110

of cover plate 24 and in the central flange is a transverse slot 47 in which is located a short pin 48 eccentrically mounted on a disk 49. Disk 49 is carried on the inner end of shaft 50 pivotally mounted in an opening in cover plate 24, the disk being located in a recess in the cover plate so its outer surface is flush with the inner surface of the cover plate. On the outer end of shaft 50 is detachably fastened a handle 51 for turning shaft 50 to move the shifter block up and down. Handle 51 may be detachably fastened to shaft 50 by screwing its end into a threaded socket in the shaft and fastening it with a set screw 52 as shown in Fig. 1. The extent of the movement of the shifter block by the eccentric pin 48 is limited by the pin striking the end of slot 47, the slot being of a length to permit of the desired throw in each direction. When handle 51 is in vertical position as shown in Fig. 1, the gearing is in neutral position and it is held in this position by a spring pressed detent 53 which engages a recess in shaft 50. At this time pin 48 stands at the end of slot 47. When handle 51 is moved forward from the position shown in Fig. 1, pin 48 is elevated and lifts shifter block 41 to bring pinion 37 into mesh with gear wheel 21. The throw of the shaft is such that pin 48 moves slightly past center and therefore serves to lock the gearing in mesh. When handle 51 is moved backward from the position shown in Fig. 1, shifter block 41 is lowered to bring pinion 38 into engagement with gear wheel 21. In this case the weight of the parts serves to hold the gearing in mesh. The central forks 45 are made sufficiently long so that they engage the face of pinion 21 and thus serve when the gearing is assembled to hold the crown gear and its shaft 20 in position. The opening 26 in which bearing bushing 27 is mounted is large enough so that pinions 37 and 38 can slide through it. In assembling the gearing, the crown gear wheel 21 is put into place by inserting shaft 20 into bearing 19 after which shaft 36 with pinions 37 and 38 thereon is passed down through opening 26 to bring the lower end of the shaft into bearing 29. The bearing bushing 27 is then put into position. Following this the shifter block 41 is put into position after which cover plate 24, upon which previously has been assembled the shaft 50 and handle 51, is put into position with pin 48 in slot 47, and fastened by screws 25, the upper screw serving to fasten bushing 27 in position by reason of its end engaging in opening 28. During the assembling and before the cover plate is put into position, a suitable supply of grease may be put into the casing. Thus it will be seen that the cover plate serves to hold the entire gearing assembled since it directly engages the shifter block which in turn engages the

crown gear wheel holding it against the face of partition wall 18 which, as shown in Fig. 1, has a forwardly projecting finished surface against which the back of the gear rests. The shifter block 41 serves to hold the pinions 37 and 38 and shaft 36 in neutral position with the pinions within the confines of the teeth of gear wheel 21. 70

The cover and eccentric form a unit which is easily assembled by inserting shaft 75 50 into the bearing opening in cover plate 24 and fastening handle 51 in place, the handle serving to hold the parts in assembled position. 75

With the above-described arrangement, it 80 will be seen that the gearing can be easily and quickly assembled and also easily and quickly dismantled. Furthermore, it comprises a minimum number of parts to be manufactured, all of which are simple in 85 structure. This means that it can be manufactured at a low cost. 85

The construction is also small and compact and in this connection I regard the use 90 of a crown gear wheel as being one important feature of my improved construction since it permits of the pinions being mounted within the confines of the gear wheel so that they require no additional space. Also the use of a crown gear wheel permits of the 95 pinions being assembled by being inserted axially into position as already explained. Because of this, the casing can be made all in one piece, and still leave the assembling of the gearing a very simple matter. 100

The gearing forms a complete unit in itself which is easily attached to the wringer frame by the screws 16, at the same time being attached to lower wringer shaft 5 by coupling 9 by simply inserting the shaft 105 ends into the openings in the ends of the coupling. 105

When assembled, the middle flange 46 on the shifter block holds disk 49 in the recess in cover plate 24 so as to keep shaft 50 in position with handle 51 spaced away from the cover plate. It will thus be seen that by having the shifter block slide between the cover plate and the crown gear wheel and in engagement with both of them, it serves 110 to hold all the moving parts in correct relation to each other. 115

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means. 120

What I claim as new and desire to secure by Letters Patent of the United States, is:—

1. In a wringer, the combination of a 125 casing, a crown gear wheel journaled in a 130

- wall of the casing, a shaft which extends parallel to the face of the crown gear wheel, pinion means on the shaft located within the confines of the crown gear wheel, a shifter block for said pinion shaft, said block having a part which engages the face of the crown gear wheel to hold it in its bearing, and means for moving the shifter block to bring the pinion means into engagement with the crown gear wheel.
2. In a wringer, the combination of a casing having a rear wall and an open front, a crown gear wheel journaled in the rear wall, a shaft which extends parallel to the face of said gear wheel, pinion means on said shaft located within the confines of said crown gear wheel, a shifter block for said pinion shaft, said block having a part which engages the face of the crown gear wheel to hold it in its bearing, a cover plate for the open end of said casing, and means carried by the cover plate for engaging and moving the shifter block.
3. In a wringer, the combination of a casing having a rear wall and an open front, a forwardly-facing gear wheel journaled in said rear wall, a shaft which extends parallel to the face of said gear wheel and is journaled in the top and bottom walls of said casing, said shaft being movable axially in its bearing, pinion members fixed on said shaft and adapted to mesh with said gear wheel, a shifter block in the casing engaging said pinions and shaft, said block having a part for engagement with the surface of said gear wheel, a cover plate for the casing, said cover plate engaging the shifter block to hold it in position, and means carried by the cover plate for moving the shifter block.
4. In a wringer, the combination of a casing comprising a surrounding wall and an open front, a crown gear wheel journaled in the casing, a shaft, pinions on the shaft adapted to mesh with the crown gear wheel, an opening in the surrounding wall of the casing through which said shaft and pinions may be inserted into the casing, a bearing in said opening for one end of the shaft, a shifter block for the shaft, a cover plate for the open front of the casing, and means carried by the cover plate for moving the shifter block.
5. In a wringer, the combination of a gear casing, a wall in the casing, a crown gear wheel journaled in said wall, a shaft which is journaled in walls of the casing and extends parallel to the face of the crown gear wheel, pinion means on said shaft, said pinion means being located within the confines of the crown gear wheel, and means for moving said pinion means into and out of mesh with said crown gear wheel.
6. In a wringer, the combination of a casing having an open front, a gear wheel journaled in the casing and connected to the wringer rolls, a shaft journaled in walls of the casing, pinion means on the shaft, a shifter block for moving the pinion means into and out of engagement with the gear wheel, a cover plate for the open front of the casing, and means journaled in the cover plate for moving the shifter block, said means including an eccentric pin and slot connection.
7. In a wringer, the combination of a casing having an open front, a gear wheel journaled in the casing and connected to the wringer rolls, a shaft journaled in walls of the casing, pinion means on the shaft, a shifter block for moving the pinion means into and out of engagement with the gear wheel, said shifter block having a slot therein, a cover plate for the open front of the casing, and an eccentric pin carried by the cover plate and engaging said slot for moving the shifter block.
8. In a clothes wringer, the combination of a casing having an open front, a gear wheel journaled therein and facing toward the open front, pinions for engaging said gear wheel, a cover plate for said open front, a shifter block for the pinions held between the cover plate and said gear wheel, and means for moving the shifter block.

In witness whereof, I have hereunto set my hand this 23rd day of May, 1924.

GEORGE E. RANDLE.
